UNITED STATES PATENT OFFICE.

JOHN J. HOGAN, OF MIDDLETOWN, NEW YORK.

DESIGN FOR A TUBULAR STEAM-BOILER.

SPECIFICATION forming part of Design No. 25,201, dated February 25, 1896.

Application filed September 10, 1895. Serial No. 562,111. Term of patent 14 years.

To all whom it may concern:

Be it known that I, JOHN J. HOGAN, a citizen of the United States, residing at Middletown, county of Orange, and State of New York, have invented a certain new and useful Design for Tubular Steam-Boilers, fully described and represented in the following specification and the accompanying drawings, forming a part of the same.

10 This invention consists in a novel shape or configuration for the tubes and drums in a tubular steam-boiler, which shape is illustrated in the annexed drawings, in which—

15 Figure 1 is a front elevation of the boiler, and Fig. 2 is a perspective view of the same.

The boiler is formed with a cylindrical body or drum A at the top and cylindrical bodies or drums B B at the bottom of the boiler at its opposite sides. Three groups of tubes C,

20 D and E are extended between each of the drums B and the drum A. The tubes C are extended first upwardly vertically from the tops of the drums B and then inwardly to the outer sides of the drum A. The tubes D

25 extend from the inner and upper sides of the

drums B toward the middle line of the boiler and at their upper ends radially to the drum A. The tubes E extend upward from the tops of the drums B, intermediate to the groups of tubes C and D, and then inwardly 30 at their upper ends to the outer sides of the drum A, with spaces C' and D' between the several groups of tubes.

The design consists in the shape or configuration of the cylindrical bodies A and B B 35 and the groups of tubes C, D and E, shaped as described and extended between the cylindrical bodies, substantially as shown in the drawings.

Having thus set forth the invention, what 40 is claimed herein is—

The design for a tubular boiler, as herein shown and described.

In testimony whereof I have hereunto set my hand in the presence of two subscribing 45 witnesses.

Witnesses:

JOHN J. HOGAN.
THOMAS S. CRANE,
W. D. BROWN.
